US00D785876S

(12) **United States Design Patent** (10) **Patent No.:** **US D785,876 S**
Cho et al. (45) **Date of Patent:** **** May 2, 2017**

(54) **WASHING MACHINE**

(71) Applicant: **Samsung Electronics Co., Ltd.**, Suwon-si, Gyeonggi-do (KR)

(72) Inventors: **Chul-Yong Cho**, Seoul (KR); **Jongsu Jeon**, Sungnam-si (KR); **Chris Bangle**, Clavesana (IT); **Seonju Lee**, Seoul (KR)

(73) Assignee: **SAMSUNG ELECTRONICS CO., LTD.**, Suwon-si, Gyeonggi-Do (KR)

(**) Term: **15 Years**

(21) Appl. No.: **29/546,948**

(22) Filed: **Nov. 30, 2015**

Related U.S. Application Data

(63) Continuation of application No. 29/441,399, filed on Jan. 4, 2013, now abandoned.

(30) **Foreign Application Priority Data**

CLAIM

We claim the ornamental design for a washing machine, as shown and described.

DESCRIPTION

FIG. 1 is a front perspective view of a washing machine showing our new design;

FIG. 2 is a front view thereof;

FIG. 3 is a rear view thereof;

FIG. 4 is a left-side view thereof;

FIG. 5 is a right-side view thereof;

(Continued)

FIG. 6 is a top view thereof; and,
 FIG. 7 is a bottom view thereof.
 The broken lines in the figures form no part of the claimed design. The unshaded areas bounded by broken lines form no part of the claimed design. The unshaded areas bounded by a combination of solid and broken lines form no part of the claimed design.

1 Claim, 7 Drawing Sheets
